UNITED STATES PATENT OFFICE.

CHARLES P. KLOMER, OF PITTSBURGH, PENNSYLVANIA, ASSIGNOR TO MILLER SAW-TRIMMER COMPANY, OF PITTSBURGH, PENNSYLVANIA, A CORPORATION OF PENNSYLVANIA.

SHEET-REGISTERING DEVICE.

1,419,148.

Specification of Letters Patent. Patented June 13, 1922.

Application filed January 24, 1920. Serial No. 353,709.

To all whom it may concern:

Be it known that I, CHARLES P. KLOMER, a citizen of the United States, residing at Pittsburgh, in the county of Allegheny and 5 State of Pennsylvania, have invented new and useful Improvements in Sheet-Registering Devices, of which the following is a specification.

My invention pertains to sheet registering 10 devices and relates particularly to registering devices for use in connection with platen printing presses, especially those of the Gordon type.

It is an object of my invention to provide 15 an automatic device for bringing sheets to be printed into a correct registering position upon the surface to which they are fed, which will be of a simple construction and cheap to produce, which will be durable in 20 use, which will be accurate and reliable in operation, and in which the number of parts will be reduced to a minimum. Other objects of my invention will appear from the following specification and claims.

25 I have shown, by way of example, in the accompanying drawings, and described in the following specification, one form of register device constructed in accordance with my invention. In these drawings.

30 Fig. 1 is a plan of the platen of a Gordon press having a register device of my invention attached thereto, the platen grippers being in the position they assume during the feeding of a sheet.

35 Fig. 2 is an enlarged plan of the register device;

Fig. 3 is a section taken on the line 3—3 of Fig. 2, looking in the direction of the arrows; and

40 Fig. 4 is a section taken on the line 4—4 of Fig. 2, looking in the direction of the arrows.

In the following specification, the register device of my invention is described as applied 45 to the platen of a job press of the Gordon type. Such a press comprises a platen 10, mounted so as to be capable of being rocked into and out of printing relation with the type-bed of the press, and having bails 11 for securing a tympan 12 thereon. A gripper bar 13 is mounted to rock in bearings carried by the platen and has grippers 14 mounted thereon so as to be longitudinally adjustable thereof. When the

55 platen is adjacent printing position, the grippers 14 press downwardly upon the sheet to be printed, the top of the gripper bar 13 being then approximately parallel with the surface of the tympan. When, however, the platen is in position for receiving a sheet, the grippers 14 are raised from the platen as indicated in the drawings, the gripper bar having then rocked to a position in which its top is at an angle to the surface of the platen (Fig. #3). In applying the register device, the gripper bar 13 has a portion of the rear ledge 15 cut away, as at 16.

50 A register block is secured to the platen at the center of the front thereof. This 70 block includes a top portion 17 formed with a longitudinal groove 18 having a number of tapped holes 19 therein. Extending downward from the top portion 17 is a web 20 which lies closely to the front edge of 75 the platen and has a flange 21 extending at right angles therefrom beneath the platen. A pair of holes 22 are formed in the flange 21, through which holes pass stems 23 having collars 24 formed thereon. The flange 21 80 engages against the collars 24 and is held in such engagement by nuts 25. The stems 23 are threaded into the platen, and extend through to the top of the latter. By adjusting the stems in the platen, the position 85 of the top of the register block, relatively to the surface of the platen may readily be adjusted.

80 The register device herein described comprises a base 26 stamped from sheet metal 90 and formed with a pair of tongues 27 adapted to enter the groove 18 of the register block. The base is secured in position by means of a screw 28 entering one or another of the holes 19 in the register block. The base 26 is formed at the rear with a pair of spaced sockets 29 for receiving a pin 30. Upon the pin 30, between the sockets 29, is rockably mounted an arm 31 having an upwardly extending fork 32 carrying a pin 33. The arm 31 lies upon the top of the gripper bar 13 with its end beneath a bail 34 with which the gripper bar is provided. This being the case, when the gripper bar 100 is rocked from the position shown in Fig. 3 to a position in which its top is substantially 105 parallel with the platen surface, the pin 33 will be moved towards the platen.

Upon the pin 33 is rockably mounted an arm 35 having its end bent down, at 36, and terminating in a ball 37. The ball 37 is mounted in a socket 38 secured to one end of 5 a flat swinging arm 39. The arm 39 is pivoted to the base 26 by means of a pin 40, and is bent at its end so as to form a socket 41, rectangular in cross-section, for receiving the shank of a register finger 42. A screw 10 43, operating upon a bearer plate 44, serves to hold the register finger in position in the socket. The register finger 42 terminates in a fork 45 for receiving the edge of a sheet fed to the platen.

15 The sheets are fed to the platen when the register finger and other parts are in the position shown in the drawings. The sheet, designated 46 in the drawings, will often be fed so as to engage in the fork in an out-of- 20 register position such as is indicated in full lines in Fig. 1. As the platen rocks from feeding toward printing position, the gripper bar rocks from the position shown toward a 25 position in which its top will be parallel with the platen surface. This movement of the gripper bar causes the ball 37 to push the socket 38 towards the platen, thereby causing the arm 39 to swing about its pivot 43. The fork 45 of the register arm is thus caused to 30 describe an arc of a circle having the pin 40 as its center, and is brought into the position shown in dotted lines in Fig. 1, with one side and one end of the sheet in engagement with the end register pins 47 and side register pin 48, the fork sliding off the sheet after 35 it has thus brought it into perfect register.

A register device of my invention constructed as described above comprises but few parts, and these parts are of a sturdy 40 nature and capable of enduring heavy and continuous use. The construction is simple and cheap, and the application of the device to a press necessitates but a very slight amount of work on the latter. The device, 45 moreover, can be depended upon always to perform its intended function accurately and efficiently.

I have given above a detailed description of 50 one form of register device in which my invention may be embodied; but I wish it understood that my invention may be embodied in other forms, and that changes may be made in the particular form described and shown, without exceeding the scope of my 55 invention, what I claim being—

1. A sheet registering device comprising a base for attachment to a platen, an arm pivoted to said base, a sheet-gripping member connected with said arm at one side of its 60 pivot, and a foot pivoted to said base for cooperative engagement with the gripper bar of said platen, said foot being connected with said arm at the other side of the pivot of the latter.

65 2. A sheet registering device comprising a

base for attachment to a platen, a lever pivoted to said base and having a foot for cooperative engagement with the gripper bar of said platen and having an upwardly extending arm, a member movably connected with 70 said base and having sheet engaging means associated therewith, and a link pivoted to said arm and connected with said member.

3. A sheet registering device comprising a base for attachment to a platen, a lever pivoted to said base and having a foot for cooperative engagement with the gripper bar of said platen and having an upwardly extending arm, a member movably connected with 75 said base and having sheet engaging means associated therewith, and a link pivoted to said arm and having a ball and socket connection with said member.

4. A sheet registering device comprising a base for attachment to a platen, a lever pivoted to said base and having a foot for cooperative engagement with the gripper bar of said platen, and having an upwardly extending arm, a member pivoted to said base, 85 a sheet engaging device carried by said member, and a link pivoted to said arm and having a ball and socket connection with said member.

5. A sheet registering device comprising a base for attachment to a platen, a lever pivoted to said base having a foot for cooperative engagement with the gripper bar of said platen and having an upwardly extending arm, a member pivoted intermediate its ends 90 to said base, a sheet engaging device carried 100 by said member at one end, and means for connecting the other end of said member with said arm.

6. A sheet registering device comprising a base for attachment to a platen, a lever pivoted to said base having a foot for cooperative engagement with the gripper bar of said platen and having an upwardly extending arm, a member pivoted between its ends to 105 said base, a sheet engaging device connected with said member at one end to the latter, and a link pivoted to said arm and having a ball and socket connection with the other end of said member.

7. A sheet registering device comprising a base for attachment to a platen, said base having an upwardly projecting bearing, a bell-crank lever pivotally mounted in said bearing and having an arm for cooperatively engaging the gripper bar of said platen and another arm extending upwardly, a member pivoted intermediate its ends to said base and having a socket at one end, a sheet engaging device adjustably mounted in said socket, and means for connecting the other 120 end of said member with said upwardly extending arm.

8. A sheet registering device comprising a base for attachment to a platen and having an upwardly projecting bearing, a bell-crank 125

lever pivotally mounted in said bearing having an arm for cooperative engagement with the gripper bar of said platen and another arm extending upwardly, a member pivoted intermediate its ends to said base and having a

ball and socket connection with the other end of said member.
